UNITED STATES PATENT OFFICE.

ANTONIO RAUSSE, OF NORTHVALE, NEW JERSEY.

ATTACHMENT FOR PRUNING SHEARS.

1,426,214.

Specification of Letters Patent. Patented Aug. 15, 1922.

Application filed April 1, 1922. Serial No. 548,746.

To all whom it may concern:

Be it known that I, ANTONIO RAUSSE, a citizen of the United States, and a resident of Northvale, in the county of Bergen and 5 State of New Jersey, have invented new and useful Improvements in Attachments for Pruning Shears, of which the following is a full, clear, and exact description.

This invention relates to a handle fastener for tools of the scissors type.

In the operation of a pruning shears or other tools of the scissors type, which are controlled by a spring normally forcing the handles outward, it is often necessary to 10 provide some means for holding the handles closed in order to slip the tool into the pocket when not in use. When using a pruning shears it is usually found that it is inconvenient to free both hands in order to 15 operate the means for holding the handles closed. This may be the case with using other tools of the same type. Hence a tool provided with means for holding the handles closed which is capable of easy operation by 20 one hand would be of considerable value.

The general object of this invention is the provision of a cheap, efficient and simple fastening means for use in conjunction with tools of the scissors type, provided with 25 means for locking the handles closed when not in use, and means for retaining the locking means in an inactive position when the tool is being operated.

This object is accomplished by providing, 30 on one handle of the tool, latch means, and on the other, means capable of being engaged by the latch means, and associating with the latch means means for normally retaining the latch in an inactive position 35 when the tool is being operated.

This and other objects of the invention will be more clearly understood from the following detailed description and accompanying drawings, in which—

40 Figure 1 is a top plan view of a pruning shears with part broken away to show details of the fastening attachment;

45 Figure 2 is a plan view of a portion of the handles of the pruning shears showing the attachment;

50 Figure 3 is an end elevation of the pruning shears showing the latch.

55 Referring to the above-mentioned figures, a pruning shears, which consists of two handles 10 and 11 pivoted at 12 and provided

with jaws 13 and 14, is shown. A spring 15 is located between the handles 10 and 11 and serves to force them apart after the cutting operation has been accomplished. The handles 10 and 11 of the shears are provided 60 with inturned ends 18 and 22, respectively. The inturned end 18 of the handle 10 is forked.

Pivots mounted between the prongs of the forked end 18 of the handle 10 is a latch 65 17 the shape of a bell crank. A flattened head 19 is provided on one arm of the bell crank shaped latch. A spring 20 is interposed between the handle 10 and the inner end of the latch 17. This spring rotates the 70 latch 17 about its pivot point 23, drawing the head 19 of the latch 17 into an active position where it will engage shoulders 16 formed on the inturned end 22 of the handle 11 when the handles are brought together 75 10 and in alignment with the latch 17. A plunger 21 is slidably mounted in the handle 10 and in alignment with the latch 17.

In the operation of the shears when the handles are brought together the head 19 80 of the latch 17 engages the shoulders 16 thus locking the handles closed. If the operator desires to continue operating the handles he places his hand over the plunger 21. This forces the inner end of the latch 17 downward about its pivot point 23, carrying the head 19 to a position where it will not engage the shoulders 16 of the handle 11. As long as the plunger 21 is held in the position 85 shown in Figure 2 the shears may be operated. When the operator desires to lock the shears closed to place it in a holder or the pocket all that is necessary is to release the plunger.

I would state in conclusion that while the 90 illustrated example constitutes a practical embodiment of my invention I do not limit myself strictly to the exact details herein illustrated since manifestly the same can be 95 considerably varied without departing from 100 the spirit of the invention as defined in the appended claims.

Claims:

1. In combination with a tool of the scissors type including spring-controlled operating handles, a locking attachment comprising latch means pivoted to one handle, means in conjunction with the other handle adapted to be engaged by the latch means when the handles are brought together, 110

spring means for normally retaining the latch means in active position, and means associated with the handle for retaining the latch means out of active position while the handles are being operated.

2. In combination with a tool of the scissors type including spring-controlled operating handles, a locking attachment comprising a latch pivoted to one handle, catch means in conjunction with the other handle for engaging said latch when the handles are brought together, a spring associated with the latch for normally holding it in an active position to be engaged by said catch means when the handles are brought together, and means associated with the handles for holding the latch in an inactive

position when the handles are being operated.

3. As a new article of manufacture, a fastening device for use with tools of the scissors type including operating handles, comprising a latch pivotally mounted on one handle, latch engaging means provided in conjunction with the other handle, a spring for normally holding the latch in engagement with the latch-engaging means when the handles are closed, and a plunger slidably mounted in one handle and co-operating with the latch for holding the latter in an inactive position while the handles are being operated.

ANTONIO RAUSSE.
